UNITED STATES PATENT OFFICE.

FREDERICK WILLIAM HALL, OF LONDON, ENGLAND.

COIN-COLLECTING MEANS FOR TELEPHONE SERVICES.

Application filed December 9, 1922, Serial No. 605,975, and in England December 14, 1921.

This invention relates to coin collecting means for telephone services. Its principal object is to simplify and accelerate the procedure whereby the subscriber, after inserting into a box or casing the proper number of coins, can either secure the desired connection, or in case that connection is not available, can obtain refund of the payment inserted. Other objects of the invention 10 are to effect improvements in the mechanism of the coin collector, all of which will be described fully hereinafter and pointed out in the subjoined claims.

According to the invention the insertion 15 of the coin renders the transmitter inoperative, but also renders operative a device for communication between the subscriber and the exchange, enabling the subscriber to communicate or select the connection he requires. 20 Means are provided whereby the subscriber can alternatively "cash in" or "cash out" the inserted coin. If he obtains the required connection, and cashes in, the act of so doing renders the transmitter operative again, for 25 conversation with the selected correspondent. If on the other hand the subscriber cashes out, the act of so doing does not render the transmitter operative, and conversation cannot be had, without intervention of the 30 exchange, until a fresh payment has been made and has been cashed in.

We may also arrange for rendering operative a signalling device and disabling the transmitter both by the cashing in and the 35 cashing out movements.

Apparatus embodying this novel arrangement is shown in the annexed drawings.

Fig. 1 is a diagram showing one arrangement of circuits and contacts for the purpose, for use with a manual telephone system.

Figs. 2 and 3 being views of mechanism comprised in a coin collector for actuating and controlling the said contacts.

Fig. 4 shows a modification of part of the 45 said mechanism.

Fig. 5 is a diagram, showing an arrangement of circuits for use with an automatic telephone system.

Figs. 6 to 9 are views of coin collecting 50 mechanism with an arrangement of contacts appropriate to an automatic telephone system.

Fig. 10 illustrates another modification.

In Fig. 1 the parts are shown in normal 55 position, prior to insertion of coins into the

box. The receiver 1 is operative and remains operative at all times. Shunted on one side of the line in a polarized relay 2, adapted to open and close a contact 3 in a 60 shunt circuit whereby the transmitter T can be short circuited. Included in this shunt circuit are also two contacts 4, 5, the closing of which, when contact 3 is closed completes the short circuit. When open, the contact 65 member 5 makes contact at 6, cutting out the relay thus removing its resistance from the line. Bridged across the line at the caller's station is the coil of an electric bell 7, and from the middle of this coil a wire leads to 70 a contact 8, for making an earth connection, this being the calling contact for operating an earthed calling lamp or relay at the exchange. Connected in parallel with a resistance in the line is a buzzer relay 9, which is 75 normally short circuited by a contact 10, and the purpose of which will be explained hereinafter.

I will now proceed to describe the coin-collecting mechanism whereof portions are 80 shown in Figs. 2 and 3.

This mechanism is arranged within a case having a coin slot whence the inserted coins pass through a short vertical intake chute behind the wall 11 (Fig. 2), into an 85 inclined chute which conducts the coins to a vertical chute is formed between a plate 14 and a plate or flap 15 behind the same. The flap 15 is hinged to lugs 16 near the top, so that it can swing outwards at the bottom. 90 The outward swing being limited by a coil spring on the shank of a screw 17 which passes through a hole in the flap. This spring is of sufficient strength to enable the flap to hold lightly in proper position the 95 normal or maximum number of coins for which the machine is intended, but allows the flap to yield if the coins show any tendency to become wedged in the chute. Pivoted at 18 near the top of the chute 13 100 to the outside of the plate 14 is a rocker in the form of a quadrant 19 having an arm 20. Pivoted to a bracket 21 below the quadrant there is a trip lever 22 in the form of a hook with a series of teeth or steps which 105 form a zig zag passage therein. At its upper end this trip lever has a pin 23 fixed to it, which projects through a slot into the chute 13. Pivoted to a bracket 24 on the plate 14 is a double armed balance lever 110 25 having an adjustable weight 26 on its shorter arm. The longer arm of

the balance lever has its free end bent over at a right angle to project through a slot 27 into the chute 13 after passing through the passage in the trip lever 22 and through an aperture in the quadrant 19. The edge of this aperture in the quadrant conforms in part to the arc described by the end of the balance arm, so that until the arm is lowered the quadrant cannot be 10 swung, but the lower part of the aperture is enlarged so that when the arm has reached the bottom of the slot 27 the quadrant can be rocked.

Each coin of the proper denomination and 15 weight entering the chute 13 first strikes the pin 23 and thus swings the trip into the position shown in Fig. 2, then clears this pin and drops on to the bent end of the balance lever 25, which it depresses, the 20 balance arm sliding off the first step on the right hand side of the zig-zag path, and being arrested by the first step on the left hand side when the trip lever swings back to normal position. The next coin inserted 25 swings the trip lever again, and enables the balance arm, weighted by both coins, to swing down to the next step on the left hand side. The third coin completes the release of the balance arm, and the same 30 then descends to the bottom of the slot 27.

Each time the trip lever 22 is rocked by a coin, a short arm projecting from its foot lifts a leaf spring, which carries the contact 10 already referred to with reference to Fig. 35 1. The contact 10 is thus temporarily opened and the buzzer 9 is energized so that the insertion of the coin is signalled at the exchange.

When the balance arm 25 drops to its 40 lowest position a tappet 28 thereon bends a leaf spring which carries the contact 8 already referred to, thus closing this contact, which calls up exchange when the receiver is removed from the switch hook.

Pivoted to the arm 20 of the quadrant 45 19 is a link 29 having a slot whereby it engages a stud on an arm 30 pivoted at 31 to the plate 14. On the pivot 31 there is also mounted a lever 32, which has a stud 33 engaging the arm 30. Fixed to the lever 50 32 is a pin 34 projecting through a slot into the coin chute 11 so that when a coin (indicated by a broken line in Fig. 2) is pushed into the chute it rocks the lever 32, whose 55 stud 33 rocks the arm 30. The latter has a notched tail piece, which is engaged by a spring catch 35 to hold it in its normal position as shown in Fig. 2 or in another position into which the arm can be rocked by 60 the stud 33. The tail piece of the arm 30 has a stud 36 engaging a leaf spring, which is the contact 5 referred to in connection with Fig. 1 and is disposed between two 65 springs, which are the contacts 4 and 6.

When the arm 30 is rocked by the stud 33 65 the stud 36 removes the contact 5 from the contact 6 and presses it against the contact 4. Contact between 5 and 4 is maintained, after the passage of the coin by the engagement of the tail piece with the catch 35. 70

Mounted alongside the arm 20 of the quadrant is a rock shaft 37 having two parallel arms 38 engaging a push button 39 and having also an arm 40 adapted to engage the arm 20 of the quadrant, so that 75 by actuating the push the arm 20 is depressed. The arm 40 is connected by a link 41 to one of two pivoted arms 42 which carry the inclined chute 12. When the push is actuated the arm 40, by means of the said 80 link, rocks the chute 12, and when the push is released the weight of the chute restores the arm 40 and the rock shaft to normal position.

It will be seen that depression of the 85 arm 20 by the arm 40 swings the quadrant 19 to the left, as viewed in Fig. 2.

Pivoted at 43 is a double armed lever 44, which can be actuated by means of a push 45, and when so actuated lifts the arm 20, 90 in order to swing the quadrant 19 to the right, as viewed in Fig. 2.

Fixed to the quadrant 19 are two pins 46 projecting through slots into the chute 13. When the balance arm 25 has been fully 95 lowered by the insertion of the proper number of coins the coins lie between the pins 36. If the quadrant is swung to the left, by actuating the push 39, the right hand pin 46 ejects the coins into the till. If on the other hand the quadrant is swung to the right by actuating the push 45, the left hand pin 46 ejects the coins into a chute which returns them to the customer.

It will be seen that the effect of inserting 105 the coins into the box is to close at 4, 5 the shunt circuit which renders the transmitter inoperative, to actuate the contact 10 and thus signal the insertion of each coin at the exchange, and to call up exchange by means 110 of the contact 8. For answering the call the exchange operator opens the contact 3 by means of relay 2, thus breaking the shunt circuit. The relay 2 is operated by operating 115 a reversing key, which reverses the current in the line. When the subscriber has stated his requirement the operator closes the shunt circuit again. If the subscriber has received the required connection he actuates the push 39, thus causing the payment to 120 enter the till. At the same time the rocking of the arm 20, which pulls down the link 29, actuates the arm 30, thus breaking the shunt circuit at 4, 5 and short circuiting the relay at 5, 6. If he has not got the connection required, he actuates the push 45 and thus causes the coins to be ejected from 125 the box and refunded.

In the modification shown in Fig. 4 the approximately vertical chute into which the coins pass from the inclined chute is designated 13^a, and is a conduit fixed to the 5 quadrant 19 by means of screws 13^b which pass through slots in the plate 14, so that the conduit swings with the quadrant. We have also here shown a deflector in the form of a bent plate 47 pivoted at 47^a so that it 10 is suspended behind the chute 13^a. Until the balance arm 25 has been fully depressed by insertion of the normal number of coins for payment of an ordinary call the plate 47 is held away from the chute by the end of 15 the balance arm, as shown in Fig. 4, but when the arm has been depressed the curved lower part of the deflector plate 47 allows the same to swing inwards by gravity (if desired assisted by the action of a spring not 20 shown.) By this movement a portion of the plate 47 is interposed between the chute 13^a and the outlet of the inclined chute 12, so that if additional coins are inserted, as for example by way of extra payment for 25 a call beyond a certain radius, such coins are deflected by the plate into a separate receptacle. By this means the extra payments are, for purposes of accountancy or statistics, kept separate from the normal or so-called "toll" payments.

In the apparatus shown in Figs. 6 to 9 the construction and arrangement of the chutes, quadrant, trip lever and balance arm, and the means for actuating the same, are 35 the same as in Figs. 2 and 3. For parts which are identical with corresponding parts in Figs. 2 and 3 I have used the same reference numerals, with an affix applied thereto as 11¹, 12¹ etc. The arrangement of the 40 contacts is, however in part different, the apparatus being intended for use in an automatic telephone system as shown in Fig. 5. The depression of the balance arm 25¹ with the tappet 28¹ closes the contact 48 and opens 45 the contact 50. The effect of this is to render the transmitter inoperative and the selector dial 90 operative, so that the subscriber can adjust the dial for the communication required but cannot then at once avail 50 himself of the transmitter. If the communication is obtained, the payment is cashed in by pressing the push 39¹, whereupon the ascending balance arm allows the contacts 48 and 50 to return to normal, and the transmitter thus becomes operative. If the communication is not obtained the payment is cashed out by operating the push 45¹. This 55 also renders the transmitter operative again, but the push 45¹ opens a frictionally pivoted contact 49, which breaks the line and causes the automatic selector and connector switches to be released. The opening of the contact 60 65 60 pushes in the plunger 51 of a dash-pot, which after a sufficient interval of time re-closes the contact.

In case the coin collector shown in Figs. 6 to 9 is to be used alternatively for long distance calls not within the automatic system, the subscriber having means for calling up an exchange operator and asking for the 70 manual connection required, there is provided a contact 100, which is opened by each rocking movement of the trip lever 22¹. When the operator has had an answer to the 75 call, she directs the subscriber to insert the prescribed number of coins. Each coin inserted causes the contact 100 to be opened, and this operates a buzzer 101, enabling the operator to count in the payment.

Fig. 10 shows a modification, also intended 80 for automatic systems, in which contacts 5¹¹ and 6¹¹ arranged and operated as described with reference to Fig. 2 are used, instead of the contact 50 shown in Figs. 7 and 8. For this purpose the said contacts 85 5¹¹ and 6¹¹ must be returned to normal not only by the cashing in operation, but also by cashing out. As shown in Fig. 10 this is done by means of a double armed lever 52 pivoted to the frame and connected by a 90 link 53 to the arm 30¹¹ this arm corresponding to the arm 30 in Fig. 2. The lever 52 is actuated by the upward movement of the quadrant arm 20¹¹ when the subscriber cashes out, and the link 53 then pulls down 95 the arm 30¹¹. Thus the same movement is given to the contacts as is given by the link 29¹¹ when a payment is cashed in.

The present invention also contemplates 100 the provision of means constructed and arranged as described in British Patent No. 149,361, comprising a contact breaker actuated by each coin which constitutes an extra payment or part thereof to operate a buzzer or other signal audible at the exchange so 105 that such coins or extra payments may be readily counted or checked in by the operator, and this scheme can be further extended to provide audible signals of different character to indicate the payment of coins of 110 different denomination by the provision of a separate contact breaker for each of such coins and corresponding circuits.

What I claim as my invention and desire 115 to secure by Letters Patent of the United States is:

1. In a telephone system the combination, with a transmitter, of a coin collector having means whereby the inserted coin is held in suspense, means whereby the coin so held 120 can be alternatively cashed in or cashed out by the subscriber, a device for communication between the exchange and the subscriber, means whereby the inserted coin renders the transmitter inoperative and renders operative said device for communication between the exchange and the subscriber, and means whereby the cashing in 125 of the coin renders the transmitter operative.

2. In a telephone system the combination, with a transmitter, of a coin collector having means whereby the inserted coin is held in suspense, means whereby the coin so held can be alternatively cashed in or cashed out by the subscriber, means whereby the inserted coin renders the transmitter inoperative, means controlled by the exchange for re-instating and re-disabling the transmitter, and means whereby the cashing in of the coin renders the transmitter operative, the cashing out being ineffective to reinstate the transmitter.
3. In a telephone system the combination, with a transmitter, of a coin collector having means whereby the inserted coin is held in suspense, means whereby the coin so held can be alternatively cashed in or cashed out by the subscriber, a device for communication between the exchange and the subscriber, means comprising a shunt circuit and a switch in said circuit adapted to be closed by the insertion of the coin, whereby the inserted coin renders the transmitter inoperative and renders operative said device for communication between the exchange and the subscriber, and means whereby the cashing in of the coin renders the transmitter operative.
4. In a telephone system the combination, with a transmitter, of a coin collector having means whereby the inserted coin is held in suspense, means whereby the coin so held can be alternatively cashed in or cashed out by the subscriber, means comprising a shunt circuit and a switch in said circuit adapted to be closed by the insertion of the coin whereby the inserted coin renders the transmitter inoperative, means controlled by the exchange for re-instating and re-disabling the transmitter, and means whereby the cashing in of the coin renders the transmitter operative, the cashing out being ineffective to reinstate the transmitter.
5. In a telephone system the combination, with a transmitter, of a coin collector having means whereby the inserted coin is held in suspense, means whereby the coin so held can be alternatively cashed in or cashed out by the subscriber, means whereby the inserted coin renders the transmitter inoperative, means controlled by the exchange for re-instating and re-disabling the transmitter, said means including switch devices whereby communication can be had with the exchange, and means whereby the cashing in of the coin renders the transmitter operative and short circuits said switch devices, the cashing out being ineffective to reinstate the transmitter.
6. The combination claimed in claim 1, together with means whereby the act of cashing out causes the line to be disconnected for a predetermined period of time.
7. The combination claimed in claim 1, with a contact breaker actuated by each coin inserted for an extra payment, to operate an audible signal at the exchange.
8. The combination claimed in claim 2, with a contact breaker actuated by each coin inserted for an extra payment, to operate an audible signal device at the exchange.
9. The combination claimed in claim 1 with means whereby the act of cashing out causes the line to be disconnected for a predetermined period of time and separate contact breakers for coins of different denominations for operating audible signals of different characters.
10. In a telephone system the combination of a transmitter, a coin collector having means whereby the inserted coin is held in suspense, means actuatable manually by a subscriber whereby the coin so held can alternatively be cashed in or cashed out, a device actuated by the inserted coin for rendering the transmitter inoperative, means whereby, after the inserted coin has actuated said device and while the coin is held in suspense, the subscriber is enabled to signal his requirements to the exchange, and means whereby the cashing in of the coin disables the device rendering the transmitter inoperative.

In witness whereof I have signed this 95 specification.

FREDERICK WILLIAM HALL.
